(57) **CLAIM**

The ornamental design for a light guide device for LED lamp, as shown and described.

DESCRIPTION

FIG. 1 is a perspective view of a light guide device for LED lamp showing my design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a view of section A-A of FIG. 1, shown at an enlarged scale;

FIG. 9 is a sectional view of section B-B of FIG. 2, shown at an enlarged scale; and,

FIG. 10 is a sectional side view of section B1-B1 of FIG. 2, shown at an enlarged scale.

The broken lines showing in the drawings are for the purpose of illustrating environmental structure and form no part of the claimed design.
